MINIATURE HEAD GUARD

Morris E. Geldstein, Denver, Colo.

Application August 12, 1940, Serial No. 352,338

4 Claims. (Cl. 40—1.5)

This invention relates to miniature head guards to be worn as a souvenir or badge and to the method of making the same and means for attaching the same to the person.

An object of the invention is to provide, as a new article of manufacture, a novelty in the form of a headguard of the type used in sports, such as football, but in miniature so that it may be worn by the person as a badge, emblem or souvenir.

A further object is to provide a new method or process of manufacture of such a headguard in a simple manner and so economically as to make possible the production and sale of the same for common use as such a badge, emblem or souvenir.

A further object is to provide improved means for attachment of such badge or souvenir to the person, which attaching means shall also include means for readily attaching and readily changing colored ribbons and the like which may be appropriate for varying situations in which such badge, emblem or souvenir is worn.

With these, and other, objects in view all of which will more fully hereinafter appear, the invention comprises certain novel constructions, combinations and arrangements of parts and certain steps and combinations of steps in the method of manufacture as will be hereinafter more fully described and claimed and as illustrated in the accompanying drawings in which—

Fig. 1 is a front elevation of the completed headguard.

Fig. 2 is a section on line 2—2 of Fig. 1.

Fig. 3 is a plan of the blank from which the skull piece is made.

Fig. 4 is a plan of the formed skull piece.

Fig. 5 is a front elevation of the formed skull piece.

Fig. 6 is a section on line 6—6 of Fig. 4.

Fig. 7 is a plan of the blank from which the band-earpiece section is made.

Fig. 8 is a plan of the band-earpiece formed ready for attachment to the skull piece.

Fig. 9 is a front elevation of the headguard with attaching means.

Fig. 10 is a side elevation of the attaching means with a sectional fragment of the skull piece showing manner of securing the attaching means to the skull piece.

Fig. 11 is a plan of a blank for the button of the attaching means.

Fig. 12 is a view of the button formed ready for assembly.

Fig. 13 is a fragment of the attaching means showing assembly of the button and strap.

Fig. 14 is a view like Fig. 13 but illustrating a modification comprising an attaching pin secured to the button.

Fig. 15 is a view like Fig. 14 but illustrating ribbons carried by the strap and button.

The novelty, which is the ultimate product and embodiment of this invention comprises, in miniature, an imitation of a football headguard consisting of three pieces, namely, a skull piece 1, a band-earpiece 2 and a chin strap 3, also an attaching strap 4 and button 5.

The simplicity and economy of construction of this novelty lies primarily in the formation of the band-earpiece as illustrated at Figs. 7 and 8.

It is assumed that this novelty is constructed of leather which is most appropriate for a football novelty, the economy of the use of leather residing in the fact that because of the small size of the parts entering into this article small scraps of leather, not adaptable for general uses, can be employed. Any other suitable material can, however, be used.

25 The description of the process or method will be in terms of leather working.

The skull piece 1 is formed of a disk, illustrated at Fig. 3, which is pressed into a cup shape as illustrated at Figs. 4, 5 and 6, in manner and by 30 means well known to and in common use by leather workers.

The skullpiece is preferably ornamented with burned lines 6 and imitation ventilation holes 7.

The band-earpiece 2 is formed from a blank 35 illustrated at Fig. 7, the body of which blank has a conformation, as illustrated, adapted to encircle the lower portion of the skull-piece in the manner illustrated at Figs. 1, 2 and 9. At the upper central portion the blank is preferably 40 peaked as at 8, for ornamentation.

Depending from the body of the band are two ears or flaps 9 to form the ear pieces of the completed guard and between the flaps 9 is a flap 10 depending from the body and adapted to be 45 folded backwardly and upwardly behind the body portion, as illustrated in broken line at Fig. 8 and to project upwardly inside the skull piece and engage the edge of the skull piece between the band and the flap 10 as clearly illustrated at 50 Fig. 2.

The ends of the band are skived on respectively opposite sides as indicated at 11 to provide compact overlapping of the ends when assembled, as illustrated at Fig. 2.

55 The band-earpiece is preferably ornamented

by suitable burned lines and the ear flaps 9 are pressed out and imitation ventilation holes 14 are punched, all as clearly illustrated at Fig. 8. The lower parts of flaps 9 are also punched as at 15 to accommodate the chin strap 3 which may be of any suitable material and structure, preferably thin, narrow leather strip doubled upon itself and suitably clipped together as at 16.

In assembling the skull piece 1 and the band-earpiece 2 the flap 10 is first inserted in skull piece 1 and riveted thereto as at 17. The band is then folded upwardly against the outside of the skull piece 1, covering the rivet 17 as clearly illustrated at Fig. 2. The band is then bent around the lower portion of the skull piece and the skived ends 11 of the band overlapped and the overlapped ends secured to skull piece 1 by a rivet 18, all as clearly illustrated at Fig. 2, the assembly is then damped and molded to bring the upper edges of the band in close contact with the skull piece as illustrated at Fig. 2, the result being the complete miniature headguard illustrated at Fig. 1.

Means for suspending the headguard from the clothing are provided comprising an attaching button 5 formed from a blank illustrated at Fig. 11 of outline resembling a football, preferably ornamented with burned lines 19, to increase the resemblance, and also lines 20 for the same purpose. The button is provided with two eyes 21 through which strip 4 is threaded forming a loop 22 on the face of the button. The strip 4 is made of any suitable length and the ends are passed through an eye 24 in the top of the skull piece and knotted therebeneath as at 25, whereby the headguard is suspended from the button 5.

The complete article may be attached to the clothing of the wearer by inserting button 5 through a buttonhole, such as that in the lapel of a coat.

Strip 4 may be slid in the eyes 21 so that loop 22 may readily be enlarged to receive colored ribbons 26 as illustrated at Fig. 15. The ribbons can be readily changed so that the article can carry the ribbon colors appropriate to the school or team affiliations or sympathies of the wearer.

The button 5 may, if desired, be provided with a pin 27, on its underside whereby the article may be readily attached to any portion 59 of the clothing.

By the use of leather or some similarly relatively rigid material the skull piece and the band are held firmly in proper interrelative relationship without sewing and simply by use of the two rivets 17 and 18, combined with the securing of the band in position by its connection with the riveted flap 10 and its overlapping engagement with the skullpiece.

The article is thus given great rigidity and 10 is made most durable and substantial while material and labor of construction and assembly are kept exceedingly low.

While I have illustrated and described many 15 details of construction it will be understood that many equivalent detail structures will be apparent to those skilled in the art as usable equivalents, all according to the spirit of the invention and this specification and the drawings and within the scope of the appended claims 20 and I am not to be confined to such details as are illustrated and described.

I claim:

1. A new article of manufacture of the character described comprising in combination a cup and a band surrounding the rim portion of the cup and having its ends riveted to the cup and further secured to the cup by a flap carried by the band and folded within and riveted to the cup.

2. A new article of manufacture of the character described comprising in combination a cup and a band surrounding the rim portion of the cup and having its ends riveted to the cup and having three depending flaps, the central flap being folded within and riveted to the cup.

3. A new article of manufacture of the character described comprising in combination a cup and a band surrounding the rim portion of the cup and having its ends skived and overlapped and riveted to the cup and further secured to the cup by a flap carried by the band and folded within and riveted to the cup.

4. A new article of manufacture of the character described comprising in combination a cup and a band surrounding the rim portion of the cup and having its ends skived and overlapped and riveted to the cup and having three depending flaps, the central flap being folded within and riveted to the cup.

MORRIS E. GOLDSTEIN.
